211,326

LEISURE HOME

Darwin W. Mark, Upland, Calif., assignor to Carefree Leisure Homes, Inc., a corporation of California

Filed Oct. 30, 1967, Ser. No. 9,199

Term of patent 14 years

(Cl. D13—1)

FIG. 1

FIG. 2

FIG. 4

FIG. 3

FIG. 5

FIGURE 1 is a perspective view of a leisure home showing my new design;

FIGURE 2 is a full front elevational view thereof on a reduced scale;

FIGURE 3 is a full rear elevational view thereof on the same scale as FIGURE 2;

FIGURE 4 is a side elevational view thereof showing the side not visible in FIGURE 1; and

FIGURE 5 is a top plan view thereof.

I claim:

The ornamental design for a leisure home, substantially as shown and described.

References Cited

UNITED STATES PATENTS

391,442 10/1888 Welburn.

OTHER REFERENCES

Architect & Engineer, December 1958, page 6, church at top of page.

Domus: October 1962, pages 48 and 49, house illustration.

House & Home, December 1960, page 137, house illustration.

A. HUGO WORD, Primary Examiner.